UNITED STATES PATENT OFFICE.

LOWELL C. FREEMAN, OF KALAMAZOO, MICHIGAN.

CARBURETER FOR AN EXPLOSIVE-ENGINE.

No. 851,285.

Specification of Letters Patent.

Patented April 23, 1907.

Application filed December 19, 1906. Serial No. 348,576.

To all whom it may concern:

Be it known that I, LOWELL C. FREEMAN, a citizen of the United States, residing at the city of Kalamazoo, county of Kalamazoo, 5 State of Michigan, have invented certain new and useful Improvements in Carbureters for an Explosion-Engine, of which the following is a specification.

This invention relates to improvements in 10 carbureters for an explosion engine.

The main object of this invention is to provide an improved carbureter for an explosion engine in which the richness of the explosion mixture, that is, the proportions of air 15 and fuel, is effectively and automatically controlled, although the speed of the engine and the load may vary greatly.

Further objects, and objects relating to 20 structural details, will definitely appear from the detailed description to follow.

I accomplish the objects of my invention by the devices and means described in the following specification. The invention is clearly defined and pointed out in the claims.

25 A structure embodying the features of my invention is clearly illustrated in the accompanying drawing, forming a part of this specification, in which,

Figure 1 is a detail vertical section of a 30 structure embodying the features of my invention, taken on a line corresponding to line 1-1 of Fig. 2, looking in the direction of the little arrows at the ends of the section lines. Fig. 2 is a detail side elevation, partially in 35 vertical section.

In the drawing, similar reference characters refer to similar parts throughout both views.

Referring to the drawing, 1 represents the 40 air inlet having a fuel supply nozzle 19 projecting upwardly into the same whereby, as the air is drawn through the inlet, the fuel is drawn from the delivery nozzle.

2 represents the cylinder pipe, the cylinder not being here illustrated. The throttle valve 6 is arranged within the pipe 2, the same being preferably mounted on a suitable shaft-like stem, as clearly appears from the drawing. An auxiliary air inlet is provided between the carbureter and the throttle valve. A pair of valves are provided for controlling the inlet of air at this point. This preferably consists of a cylindrical casing 3, open at its outer end with its inner end opening into the pipe. Within this casing are cylindrical tubular valves 14 and 15, the valve

15 being slidably arranged within the casing and the valve 14 being slidably arranged within the valve 15.

The valve 14 is provided with a plurality 60 of longitudinal ports 16 preferably triangular in form, the inner ends of the ports being the larger. The valves co-act so that their movement relative to each other opens or closes these ports, the outward movement of 65 the member 14 accomplishing this result, or the inward movement of the member 15. The valve 14 is connected by the rod 13 to the governor mechanism so that it is drawn outwardly as the speed of the engine increases. 70 As the style of the governor and the connections by which this is accomplished form no part of this invention, I have not here illustrated the same.

The valve 15 is connected to the throttle 75 valve preferably as follows: On the valve stem 5 of the throttle valve is an arm 7 which is connected by the link 8 to the arm 10 on the rock shaft 12, the rock shaft being carried by a suitable arm 4. The arms 11 which are 80 rigidly connected to the rock shaft engage suitable pins 17 projecting from the collar 18 secured on the outer end of valve 15. Through this connection described, when the throttle valve is opened or closed, the valve 15 is 85 opened or closed.

A turn-buckle 9 is provided for the link 8 so that it can be adjusted to open the valve the required amount. As the velocity of the air through inlet pipe 1 increases the quantity 90 of fuel drawn from the spray nozzle 19 increases in a greater proportion than the quantity of air passing through said inlet pipe 1 and conversely. This increased velocity in inlet pipe 1 is caused either by increased speed of the motor or by further opening 95 of the throttle valve 6 or by both.

Then the object of my invention is by suitable valves to keep the ratio of the quantity of fuel drawn from the spray nozzle 19 to the 100 total quantity of air passing through both the main inlet pipe 1 and the auxiliary air valves 14-15 constant. The amount of opening of valves 14-15 which compensate the 105 quality of the mixture for changing velocities is a function of the two variable factors which are the cause of the changing velocities, namely, the position of the throttle valve and the speed of the engine.

In operation the valve 15 is controlled by 110 the operation of the throttle, it being opened or moved inwardly to uncover the ports 16

when the throttle valve is opened. The valve 14, is, as stated, connected to the engine governor, so that when the speed of the engine runs up beyond a predetermined point the valve is drawn outwardly, thereby further opening the ports 16.

I have shown and described herein the preferred means for accomplishing this result on account of its compactness and simplicity in construction; also the ease with which the parts may be accurately adjusted to secure the desired result. I desire to remark, however, that the structural details of my invention may be very greatly varied.

Having thus described my invention, what I claim as new and desire to secure by Letters Patent is:

1. In a structure of the class described, the combination with a carbureter, of a cylinder pipe; a throttle valve therefor; an auxiliary air inlet located between said carbureter and throttle valve, comprising a tubular casing; an outer tubular valve adjustably arranged in said casing, an inner tubular valve adjustably arranged within said outer valve, said inner valve having longitudinal inwardly expanding ports therein and being arranged to be actuated by an engine governor; and connections for said outer valve to said throttle valve comprising an arm on said throttle valve, a rock shaft, an arm thereon, a connecting link on said arms, means for adjusting said link, projecting pins on said outer valve, and forked arms on said rock shaft arranged to engage said pins, for the purpose specified.

2. In a structure of the class described, the combination with a carbureter, of a cylinder pipe; a throttle valve therefor; an auxiliary inlet located between said carbureter and throttle valve, comprising a tubular casing, an outer tubular valve adjustably arranged in said casing, an inner tubular valve adjustably arranged within said outer valve, said inner valve having longitudinal inwardly expanding ports therein and being arranged to be actuated by an engine governor; and connections for said outer valve to said throttle valve comprising an arm on said throttle valve, a rock shaft, an arm thereon, a connecting link on said arms, means for adjusting said link, and an arm on said rock shaft connected to said outer valve for the purpose specified.

3. In a structure of the class described, the combination with a carbureter, of a cylinder pipe; a throttle valve therefor; an auxiliary air inlet located between said carbureter and throttle valve, comprising a tubular casing, an outer tubular valve adjustably arranged in said casing, an inner tubular valve adjustably arranged within said outer valve, said inner valve having longitudinal inwardly expanding ports therein and being arranged to be actuated by an engine governor; and con-

nections for said outer valve to said throttle valve comprising an arm on said throttle valve, a rock shaft, an arm thereon, a connecting link on said arms, and an arm on said rock shaft connected to said outer valve, for the purpose specified.

4. In a structure of the class described, the combination with a carbureter, of a cylinder pipe; a throttle valve therefor; an auxiliary air inlet located between said carbureter and throttle valve, comprising a tubular casing, an outer tubular valve adjustably arranged in said casing, an inner tubular valve adjustably arranged within said outer valve, said inner valve having longitudinal inwardly expanding ports therein and being arranged to be actuated by an engine governor; and connections for said outer valve to said throttle valve, for the purpose specified.

5. In a structure of the class described, the combination with a carbureter, of a cylinder pipe; a throttle valve therefor; an auxiliary air inlet located between said carbureter and throttle valve, comprising a tubular casing, an outer tubular valve adjustably arranged in said casing, an inner tubular valve adjustably arranged within said outer valve, said inner valve having ports therein and being arranged to be actuated by an engine governor; and connections for said outer valve to said throttle valve comprising an arm on said throttle valve, a rock shaft, an arm thereon, a connecting link on said arms, means for adjusting said link, projecting pins on said outer valve, and forked arms on said rock shaft arranged to engage said pins, for the purpose specified.

6. In a structure of the class described, the combination with a carbureter, of a cylinder pipe; a throttle valve therefor; an auxiliary air inlet located between said carbureter and throttle valve, comprising a tubular casing, an outer tubular valve adjustably arranged within said casing, an inner valve adjustably arranged within said outer valve, said inner valve having ports therein and being arranged to be actuated by an engine governor; and connections for said outer valve to said throttle valve, comprising an arm on said throttle valve, a rock shaft, an arm thereon, a connecting link on said arms, means for adjusting said link, and an arm on said rock shaft connected to said outer valve, for the purpose specified.

7. In a structure of the class described, the combination with a carbureter, of a cylinder pipe; a throttle valve therefor; an auxiliary air inlet located between said carbureter and throttle valve, comprising a tubular casing, an outer tubular valve adjustably arranged within said casing, an inner tubular valve adjustably arranged in said outer valve, said inner valve having ports therein and being arranged to be actuated by an engine governor; and connections for said outer valve to said throttle

valve, comprising an arm on said throttle valve, a rock shaft, an arm thereon, a connecting link on said arms, and an arm on said rock shaft connected to said outer valve, for the purpose specified.

8. In a structure of the class described, the combination with a carbureter, of a cylinder pipe; a throttle valve therefor; an auxiliary air inlet located between said carbureter and a throttle valve, comprising a tubular casing, an outer tubular valve adjustably arranged within said casing, an inner tubular valve adjustably arranged within said outer valve, said inner valve having ports therein and being arranged to be actuated by an engine governor; and connections for said outer valve to said throttle valve, for the purpose specified.

9. In a structure of the class described, the combination with a carbureter, of a cylinder pipe; a throttle valve therefor; an auxiliary air inlet located between said carbureter and

throttle valve; valves therefor; a connection for one of said valves to the said throttle valve; adjusting means for said connection, the other of said valves being arranged to be controlled by a governor mechanism, for the purpose specified.

10. In a structure of the class described, the combination with a carbureter, of a cylinder pipe; a throttle valve therefor; an auxiliary air inlet located between said carbureter and throttle; a pair of valves for controlling said air inlet; and connections for one of said valves to said throttle valve, the other valve being arranged to be controlled by a governor mechanism.

In witness whereof, I have hereunto set my hand and seal in the presence of two witnesses.

LOWELL C. FREEMAN. [L. S.]
